DESIGN FOR A STEM BASE FOR AN ELECTRON TUBE OR SIMILAR ARTICLE

Carl F. Miller, Austin, Pa., assignor to Hygrade Sylvania Corporation, Salem, Mass., a corporation of Massachusetts

Application May 16, 1940, Serial No. 92,409

Term of patent 14 years

To all whom it may concern:

Be it known that I, Carl F. Miller, a citizen of the United States of America and residing at Austin, county of Potter, State of Pennsylvania, have invented a new, original, and ornamental Design for a Stem Base for an Electron Tube or Similar Article, of which the following is a specification, reference being had to the accompanying drawing, forming a part thereof, in which:

Fig. 1 is a perspective view of a stem base for an electron tube or similar article showing my new design.

Fig. 2 is an elevational view, partly sectional, of Fig. 1.

Fig. 3 is a bottom view of Fig. 1.

This application is a continuation-in-part of application Serial No. D-79,211, filed August 10, 1938.

I claim:

The ornamental design for a stem base for an electron tube or similar article, substantially as shown,

CARL F. MILLER.
